ATTORNEY

WITNESS:

UNITED STATES PATENT OFFICE.

ALFRED YOUNG, OF JAMESTOWN, NEW YORK.

WRENCH.

1,404,079.

Specification of Letters Patent. Patented Jan. 17, 1922.

Application filed July 5, 1921. Serial No. 482,577.

To all whom it may concern:

Be it known that I, ALFRED YOUNG, a citizen of Sweden, residing at Jamestown, in the county of Chautauqua and State of New York, have invented new and useful Improvements in Wrenches, of which the following is a specification.

My present invention has reference to a quick acting wrench.

10 My object is to produce a wrench having both its stationary and movable jaws formed to provide two pairs of opposed gripping surfaces, the shank of the stationary jaw being toothed, and the carriage of the movable jaw being provided with a spring influenced pivotally supported worm for engaging the teeth, a headed element being associated with the pivotal support or the worm whereby pressure applied thereon 15 will swing the worm out of engagement with the teeth of the shank, and thus permit the quick adjustment of the movable jaw with respect to the stationary jaw.

The foregoing, and other objects which 25 will appear as the nature of the invention is better understood, may be accomplished by a construction, combination and operative association of parts, such as is disclosed by the drawings which accompany and 30 which form part of this specification.

In the drawings:

Figure 1 is a side elevation of a wrench constructed in accordance with this invention, the movable jaw being in section.

35 Figure 2 is a sectional view on the line 2—2 of Figure 1.

Figure 3 is a sectional view on the line 3—3 of Figure 2.

Referring now to the drawings in detail, 40 the numeral 1 designates the head of the stationary jaw. From the head 1 there extends the right angularly disposed shank 2 provided, on one of its edges with spaced alternating depressions and shoulders forming 45 teeth 3. The end 1 has been referred to as a head because the same projects laterally from the edges of the shank, providing the same with two engaging surfaces, 4 and 5 respectively, the object engaging surfaces, 50 of course, comprising the jaws. The jaw 5 has its engaging face arranged at a slight angle and is toothed.

Secured by plates 6 to the outer end of the shank 2 is the operating handle 7. On the 55 shank is a slidable carriage 8. The carriage

has one end widened to provide a head, the bore of the carriage being disposed centrally of the head, and thus the head provides two jaws 9 and 10 respectively, the jaw 9 being arranged opposite the jaw 4, 60 the jaw 10 opposite the jaw 5, and the said jaw 10 being disposed at a slight inclination and toothed. The carriage 8, opposite the jaw 10 is thickened, and is provided with a substantially rectangular pocket 11 that enters from the rear end of the carriage. The carriage, at its said rear end and in a line with the pocket 11 is cut away to provide parallel side walls 12. Between these walls there is a worm 13 that is designed to engage 70 with the teeth of the shank 2. The worm is mounted by a removable element 14 on a block 15 that is pivoted, as at 16 in the pocket 11. The end of the block which receives the pivot therethrough is widened, or the 75 block may be provided with a reduced portion or finger 16 that has a threaded opening therethrough. The carriage has a somewhat elongated opening 17 disposed opposite the threaded opening in the finger, and passing 80 through this opening is a stud 18 that has a reduced threaded end which is received in the threaded opening in the finger, the upper end of the stud being provided with a head 19. The numeral 20 indicates a 85 spring which has one of its ends secured in the pocket and its other end contacting the dog to swing the latter in a direction to cause the worm to engage with the teeth of the shank.

90 The operation of the wrench is believed to be obvious. When a quick adjustment is desired, pressure is exerted on the headed end of the stud which swings the block to cause the worm to be raised out of the 95 teeth of the shank. This permits the carriage being moved rapidly on the shank of the stationary jaws. When a nice adjustment is required, pressure on the stud is released and the worm is turned on the 100 thread-like teeth of the shank. The means for holding the worm on its journal is in the nature of a removable element. The pivot that holds the block in the pocket has one end headed and the other threaded, the 105 threaded end engaging a threaded opening in one of the side walls of the pocket. The stud 11 is likewise removably connected with the block, as heretofore described, and it will be thus noted that all of these parts 110

can be easily removed from the carriage should injury occur to any of the said parts. The plates 6 limit the outward movement of the carriage with respect to the stationary jaws.

Having described the invention, I claim:—

In a wrench, a headed member having a centrally arranged angularly extending shank provided on one of its edges with 10 screw teeth, a handle at the end of the shank, and plates securing the handle to the shank, a carriage having a headed portion provided with jaws which are disposed opposite the first mentioned jaws, said carriage having 15 a longitudinal pocket entering from one

end thereof and having side walls outward of the pocket, a worm between the side walls engaging the teeth of the shank, a block pivoted in the pocket having an extension providing a journal for 20 the worm, a removable element on the end of the journal securing the worm thereon, said block having a finger projection, said carriage having an elongated opening opposite the projection, a stud threadedly engaging the finger and passing through the opening, and a headed element on the outer end of the stud.

In testimony whereof, I affix my signature.

ALFRED YOUNG.
